UNITED STATES PATENT OFFICE.

CLYDE L. NORQUIST, OF JAMESTOWN, NEW YORK.

GENTLEMAN'S DRESSING CASE AND DESK.

1,410,713.

Specification of Letters Patent. Patented Mar. 28, 1922.

Application filed December 4, 1920. Serial No. 428,181.

To all whom it may concern:

Be it known that I, CLYDE L. NORQUIST, a citizen of the United States, residing at the city of Jamestown, in the county of Chautauqua and State of New York, have invented certain new and useful Improvements in Gentlemen's Dressing Cases and Desks, of which the following, taken in connection with the accompanying drawings, is a specification.

The invention relates to articles of furniture; and the improvement consists in providing a combination desk and dressing case for gentlemen, including special toilet article conveniences for holding a man's wearing apparel, making thereby a convenient piece of furniture for a gentleman's apartment; and the invention consists in the novel features and combinations hereinafter set forth and claimed.

In the drawings, Figure 1 is a perspective view of the preferred form of the combined dressing case and desk with the upper portions in the open position showing the preferred arrangement of the same; and Fig. 2 is a front elevation of the same in the closed position with the exception of the desk lid or door. Fig. 3 is an end elevation of the same with the end broken away to show the construction and arrangement of the different parts, the different parts being shown in the withdrawn or open position in dotted outline. Fig. 4 is a perspective view of a modification of the preferred form showing the desk and upper portion in the open position, and the addition of a wardrobe at one end. Fig. 5 is a top plan view of the upper tray or drawer showing a preferred arrangement for the convenience of the user. Fig. 6 is an end elevation of the display rack for the shirts in the closed position, the open or withdrawn display position being shown in dotted outline. Figure 7 is a fragmentary side elevation, partly in section showing the necktie holder, and Figure 8 is a side elevation of the necktie holder.

Like characters of reference refer to corresponding parts in the several views.

The numeral 10 designates the frame of the dressing case which is preferably provided in its lower portion with two drawers 11 and 12.

The division 13 above the drawer 11 is preferably arranged for a desk and the division 14 above said desk arrangement is

provided with a swing display rack 15 for shirts and similar articles, so that said shirts can be inserted therein and displayed by the withdrawal of said rack in graduated arrangement for quick service, as shown in dotted outline in Fig. 6, said rack being drawn into said display arrangement by the opening of the closure lid or door 16, which lid also forms a convenient rest for the garment or garments when withdrawn from the rack 15.

The shirt or garment rack 15 comprises a series of shelves 17 which are suspended at each end with a pair of pivotally attached strap supports 18 and 19, the front strap support 19 being attached to the closure door or lid 16 by a sliding support 20, both of the hanging straps 18 and 19 being pivotally suspended from the divisional partition at each end of said series of shelves. This arrangement so supports the shelves 17 that when the lid 16 is turned downward into the open position as shown in the different figures, and particularly in dotted outline in Fig. 6, said shelves 17 are drawn forward by the door and end supports 20 into the graduated display position desired for the garments on said shelves 17, for quick service in withdrawing a garment.

The upper division 29 is preferably filled by a drawer or tray 21 which is divided in different compartments for socks, shaving glass and kit, jewelry box, handkerchiefs and other articles for a gentleman's convenience in dressing.

The two divisions 13 and 14 are preferably closed by means of the door or desk lid 22 which forms a convenient writing desk, being supported by suitable sliding brackets 23 or other supporting brackets at each end, which support the lid 22 firmly in position for writing thereon. The desk portion 13 is preferably supplied with drawers and pigeon holes and has the sliding doors 24 to provide the closed compartment 25 behind said sliding doors 24 and drawers for surplus supplies of stationery and similar uses.

At each end of the divisions 13, 14 and 21, narrow vertical compartments 26 and 27 are provided for hanging neckties, a telescoping or sliding bar or tube support 28 being provided in each of said compartments 26 and 27. In the preferred form shown in Figs. 1, 2 and 3, the desk lid 22 only reaches to the under side of the division 29 so that the

tray 21 may be opened without opening either of the divisions 13 or 14 by letting down the desk lid 22.

In the modification shown in Fig. 4, a 5 wardrobe compartment 30 is provided at one end of the dresser case and the desk lid 31 differs from the lid 22 in that it extends over the top tray 21 and necktie compartments 26 and 27, as well as over the display shelf division 14 and desk division 13. The larger desk leaf 31 is not so easily supported as the smaller leaf 22. The smaller desk lid 22 when open also permits closer approach to the tray 21 in the top division 29 of the dressing case, therefore rendering the use of the shaving glass 32 and the different conveniences in the tray 21 much more convenient of approach and use.

The vertical compartments 26 and 27 provided with the extensible tubular supports 28 for neckties and similar articles of apparel, preferably have said tubular support 28 arranged in two parts 33 and 34. Part 34 has the slot 35 therein to receive the guiding stop or pin 36 in the part 33, which slot 35 has the narrower part 37 to form the stop 38 toward the inner portion of the part 34 for the pin 36, and also to provide the narrower portion 37 which receives the supporting bracket part 39 attached to the supporting plate 40 of the fixture 28 therein, thereby providing a strong and durable construction for the fixture or support 28. The fixture 28 preferably has the under hooked forward end 41 as a handle for slidably withdrawing the part 34, the neckties and other articles being hung over said part 34, an upwardly projecting stop 42 being provided on the rear end of the part 34 so that the articles hung upon the sliding support or fixture 28 are all drawn forth and supported firmly in front of the frame 10. This arrangement provides means for the instant display of a gentleman's neckties so that any particular one may be quickly seen and removed from the fixture 28, the two compartments 26 and 27 being preferably provided so that neither compartment with its fixtures 28 will be crowded.

50. What is claimed is:

1. In a dressing case, a frame having a compartment provided with vertical end walls, a series of horizontal spaced swinging shelves in the compartment, straps for mounting the shelves to permit same to swing, a closure for the compartment hinged thereto so as to swing vertically, said shelves being spaced at their ends from the respec-

tive said end walls of the compartment to form long vertical end compartments, and 60 means connected to the closure and to one of the straps for swinging the shelves forwardly upon downward movement of the closure and for holding the latter horizontal.

2. In a dressing case, a frame having a 65 compartment, a series of spaced horizontally swinging shelves in the compartment, straps for mounting the shelves to permit same to swing, a closure for the compartment hinged to the frame so as to have vertical 70 movement, and means connecting the closure to one of the straps for swinging the shelves forwardly upon downward movement of the closure and for holding the closure horizontal.

75. 3. In a dressing case, a frame having a compartment a series of horizontal shelves in the compartment, vertical pivoted straps for mounting the shelves to permit same to swing, a hinged closure for the compartment having vertical movement, and a member pivoted to the closure and to one of the straps and having a loose connection for swinging the shelves forwardly upon downward movement of the closure and for holding the latter horizontal.

4. A combined dressing case and desk comprising drawers in said case, a drop lid or door to cover the upper portion of said case, pigeon holes and small drawers in the 90 division above said lid, a series of swing display shelves in the division above said pigeon holes, a second drop lid or door to close the compartment of said shelves and means connecting said second lid to the 95 swing supports for said shelves to draw the same forward into a display and quick service position for the contents thereof, and for holding the second lid in a horizontal position.

100. 5. In a dressing case, a frame having a compartment a series of spaced swinging shelves in the compartment, a closure for the compartment hinged to the frame so as to have vertical movement, a member pivoted to the closure and having a slotted part, and a pin extending through the slot of the slotted part and connected to the shelves for moving the latter forwardly and for holding the closure horizontal.

105. In testimony whereof I have affixed my signature in the presence of two witnesses.

CLYDE L. NORQUIST,

Witnesses:

S. B. WORR,

A. I. MORAN.
